DESIGN FOR A FOUNTAIN PEN

Ford D. Cromer, Birmingham, Ala.

Application April 23, 1932, Serial No. 43,578

Term of patent 7 years

To all whom it may concern:

Be it known that I, FORD D. CROMER, a citizen of the United States, residing at Birmingham, in the county of Jefferson, and State of Alabama, have invented a new, original, and ornamental Design for Fountain Pen, of which the following is a specification, reference being had to the accompanying drawing, forming a part thereof.

In the drawing,

Fig. 1 is a side elevation of a fountain pen in an open position; and

Fig. 2 is a front elevation of the same pen in closed position showing my new design.

I claim:

The ornamental design for a fountain pen as shown.

FORD D. CROMER.
